No. 8,421

PATENTED OCT. 14, 1851.

W. H. BROWN.
SUSPENSION SHOWER BATH.

UNITED STATES PATENT OFFICE.

WILLIAM H. BROWN, OF WORCESTER, MASSACHUSETTS.

SHOWER-BATH.

Specification of Letters Patent No. 8,421, dated October 14, 1851.

To all whom it may concern:

Be it known that I, WILLIAM H. BROWN, of Worcester, in the county of Worcester and State of Massachusetts, have invented 5 new and useful Improvements in Suspension Shower-Baths; and I do hereby declare that the following is a full, clear, and exact description of the construction and operation of the same, reference being had to the 10 annexed drawings, making a part of this specification, in which—

Figure 1, is a front, back or side elevation. Fig. 2, is a vertical section through *o*, *o*; Fig. 1. Fig. 3, is a sectional plan through 15 1, 2, Figs. 1 and 2.

The same letters of reference indicate the same parts in each of the several figures.

To enable others skilled in the art to make and use my invention I will proceed fully 20 to describe it.

A, is the reservoir, made of metal in which the water for using is put.

B, is a valve at the bottom of the reservoir opening upward and worked by a screw 25 *a*, which may be turned by hand. The valve may be made of sheet rubber between disks of metal; under the valve, *B*, are holes in the reservoir for the water to pass when the valve is raised (the reservoir is open at the 30 top).

b, is a socket or box fastened to the bottom of the reservoir *A*, through which socket the screw *a*, works.

C, is the strainer made of metal and perforated with small holes in its bottom.

c is a nut for screwing on the socket or box *b*, for supporting the strainer.

D, is a conical frame to support the reservoir when not suspended and protect the 40 strainer and valve screw from injury.

d, *d*, *d*, *d*, *d*, *d*, are arms of a wire frame one end of each arm lapping round the hoop *e*, *e*, of sexagon form, and forming other ends attached to the round hoop *f*, 45 supported by hooks *g*, *g*, from the reservoir.

E, is the curtain made in one sheet of oil cloth or other material and is hung to the hooked arms *d*, *d*, *d*, *d*, *d*, by eyes or rings *h*, *h*, *h*, *h*, the perpendicular edges of 50 which curtain lap one over the other and are fastened with buttons *i*, *i*, *i*, *i*.

F, is the foot pan or tub.

k, *k*, *k*, are arms meeting together at the center, two of them being made of one piece 55 of wire forming an eye at the center and the third being hooked at the junction of

the other two—they are fixed to the reservoir and used for suspending the bath.

G, is a chain, the one end being fastened to the arms *k*, *k*, *k*, and the other end (or 60 the connection may be made at any part of the chain) to the hook *H*, forming a part of the looped strap *I*, which contains a pulley *K*.

L, is a double hook fastened in a ceiling 65 or other convenient part on which the looped strap *I*, is hung at *l*, when the bath is suspended.

M, is a fixed pulley hanging on the hook 70 *P*.

N, is a cord for raising or lowering the bath. It is fastened by a loop to a hook *L*, at *m*, and passes under the movable pulley *K*, and over the fixed pulley *M*.

Q is the direction in which the cord *N*, is 75 drawn when relieving the bath from suspension.

The operation is as follows. The bath is suspended by the chain *G*, at any one of its links to the hook *H*, which serves to regulate the height of the bucket or reservoir *A*, according to the fall desired, the hook *H*, and looped strap *I*, being supported by the hook *L*, at *l*. When required to unhitch and lower the bath, the cord *N*, is drawn in the 85 direction of *Q*, which raises the pulley *K*, toward the ceiling and in a side direction, relieving the looped strap *I*, from the hook *L*, at *l*, and by slackening the cord *N*, at *Q*, the bath descends. It is raised again by 90 pulling the cord *N*, fast at its upper end to the hook *L*, and passing over the fixed pulley *M*, the movable pulley *K*, being raised until it hitches on the hook at *l*. The shower is produced by turning the screw *a*, 95 that lifts the valve *B*, when the water in the reservoir passes through the holes in its bottom under the valve and through the perforated part or strainer *C*. The strainer *C*, can be removed at pleasure by unfastening the nut *c*, which screws on the socket *b*;

and the concealing curtain *E*, buttoned by *i*, *i*, *i*, *i*, may when the bath is not required, be unhooked from *d*, *d*, *d*, *d*, *d*, by unfastening the eyes *h*, *h*, *h*, *h*, and the curtain 100 being of a pliable material may be rolled up and put on one side; also the foot pan or tub *F*, being loose can be removed, thus offering no obstruction or inconvenience in the room when the bath is not in use as the 110 only remaining parts will be the reservoir and its appurtenances which are out of the

way against the ceiling, and when the bath is in use forming a simple elegant, and efficient arrangement. What I claim as my invention and desire to secure by Letters Patent is—

The manner of hitching and unhitching the bath for the purpose of suspending it when raised and lowering it when desired, by means of the hooks L, P, in combination

with the looped strap I, carrying a pulley 10, and K, arranged and operating in connection with another pulley M, substantially as shown and described.

WM. H. BROWN.
